CLOCK RADIO

Shuhei Taguchi, Moriguchi, Japan, assignor to Matsushita
Electric Industrial Co., Ltd., Kadoma, Japan

Filed Oct. 30, 1973, Ser. No. 411,070

Claims priority, application Japan May 7, 1973

Term of patent 14 years

Int. Cl. D14—03

U.S. Cl. D56—4 B

FIG. 1

FIG. 2

FIG. 3

FIG. 1 is a front, top and right side perspective view of a clock radio showing my new design;

FIG. 2 is a rear, top and left side perspective view; and

FIG. 3 is a front, bottom and right side perspective view in which the structure shown in FIG. 1 within the windows behind the front transparent panel has been omitted for convenience of illustration.

I claim:

The ornamental design for a clock radio, as shown and described.
